SEALED CONTAINER

Elizabeth M. Carhart, Clarendon, Va.

Application January 31, 1934, Serial No. 709,229

9 Claims. (Cl. 215—80)

The invention relates to sealing means for containers and has as an object the provision of means to provide a seal of paraffin or the like for containers having screw threaded or beaded caps.

A further object of the invention is to provide a sealed container that may be very readily opened without danger of cutting the hands.

It is a further object of the invention to provide a sealed container which will remain of value after the original contents are exhausted.

It is a further object of the invention to provide a sealed container that may be opened without recourse to any special tool.

It is a further object of the invention to provide a paraffin, wax or the like seal for screw threaded containers of glass, metal or fiber that will automatically apply the sealing material to the screw threads when the cap is applied.

Further objects of the invention will appear from the following description when read with the accompany drawing showing illustrative embodiments of the invention and wherein—

Fig. 1 is a detail perspective view of the screw threaded cap of a container,

Fig. 2 is a perspective view partly broken away of a screw cap, in place,

Fig. 3 is a detail vertical section of a modified form,

Fig. 4 is a like view of the seal of Fig. 3 in final position,

Figs. 5 and 6 are detail perspective sectional views of further modified forms of cap, and

Fig. 7 is a central vertical section of a further modification showing a possible form of tool to apply the cap.

Containers closed by screw caps have many advantages over lock seam closed containers or those to be opened by tearing metal or soldered strips. Among these advantages are the readiness with which they may be opened. No special tools, as can openers, "keys", or the like are needed. There is no danger of cutting the hands. Also, the containers are of maximum use when the original contents are exhausted.

The last named advantage is of sufficient importance to many purchasers to induce them to purchase goods offered for sale in screw-capped containers in lieu of goods in other forms of containers, if the goods are of about equal acceptability.

Heretofore it has not been possible to pack goods which must be strictly air-tight in screw-threaded containers, particularly of metal, as

they could not be readily and effectively sealed. This is particularly true of metal containers as they must be of thin metal which springs too much to permit of applying sufficient pressure upon the gasket to insure air tightness.

These difficulties are avoided in the present invention by providing means in the cap to carry a supply of congealable liquid sealing material that may be squeezed into the screw-threads either by the act of screwing the cap home or by a separate operation.

In the form of the invention illustrated in Figs. 1 and 2, the container 10 may be of glass or metal formed with the screw threads 11. The screw threaded portion is shown as joining the body of the container at the tapered portion 12. The cap 13 is shown as formed with complementary internal screw threads 14 to coact with threads 11.

To carry a supply of sealing liquid, as melted paraffin or the like, the skirt 15 of the cap is turned to form an inwardly and upwardly opening pocket 16.

When the cap is to be applied its open lower end may be dipped into the melted wax and immediately applied. When the skirt engages the inclined surface 12 the pocket 16 will be partially or wholly collapsed, thus squeezing the wax upward into the screw threads to congeal therein and form a seal. It will be seen that when the contents of the pocket are ejected the inner and lower surface of the exterior of the pocket, as at 17, will be in contact with the body of the container, thus preventing escape of the melted wax downwardly over the surface of the container.

In the form of the invention of Figs. 3 and 4, the side 18 of the container is made straight. The pocket 19 is made with the skirt flaring outwardly as shown to pass the screw threads. After this form of cap 13' is applied the pocket 19 must be collapsed by a separate operation to eject its contents. The collapsing pressure will press the inner surface of the exterior of the pocket against the body of the container, thus forcing the contents to go upwardly.

In the form of Fig. 5 the pocket for sealing material is carried in the screw threads. In this form the cap 13'' is shown as a plain cylinder, although it may flare downwardly, and the screwthreads are shown as formed by applying a ribbon of metal to the inner surface of the cylinder, as by soldering the lower edge of the ribbon to the cap, as at 21. The upper edge of the ribbon is shown as inclining inwardly,

and rolled at 22 at its edge to provide added thickness and a bearing upon the male screw-threads. The lower end 23 of the ribbon is shown as more tightly rolled to form a narrow 5 entering end of the screwthread. In this form of the invention if the sealing means is hot enough to be too limpid, it may have a tendency to flow downwardly along and out of the screw-threads before the cap can be applied to the 10 container.

To avoid the latter difficulty the form of Fig. 6 shows a roll of absorbent material 24, as wicking, carried in the pocket to hold the liquid sealing material until the cap can be applied. 15 It will be obvious that such wicking may be supplied in the pockets of the other modifications if found desirable for any reason.

Fig. 7 shows a form of the invention applicable to a bottle or container 25 having a circumferential bead 26, as distinguished from a screw-thread. The cap in this form is formed with the pocket 27 to receive the sealing material. The amount of such sealing material should be so limited as not to overflow into the container 25 when the pocket is collapsed.

I claim—

1. The method of sealing a container which comprises providing a source of supply of congealable liquid sealing material between the opposed surfaces of the container and its closure, expelling said liquid from said source by pressure to cause the liquid to flow and congeal between said surfaces.

2. The method of sealing containers which 35 comprises applying to the container a closure carrying a supply of congealable liquid, and at least partially collapsing the supply carrying means to expel the congealable liquid between the opposed surfaces of the container and closure.

3. A sealing cap for containers comprising, in combination: a closure portion; a skirt portion; an inwardly and upwardly opening, collapsible pocket carried by said skirt portion; a body of 45 sealing wax carried wholly in said pocket to be in liquid condition when the cap is applied to a container; whereby collapse of said pocket against the wall of a container may expel the wax to congeal between opposed surfaces of the skirt portion of the container.

4. A sealable container comprising, in combination: a container carrying an external ridge extending thereabout adjacent an open end; a cap formed with an internal groove to interlock 55 with said ridge; an inwardly and upwardly opening pocket carried by said cap; and a supply of congealable sealing material in said pocket

to be expelled between the cap and container by pressure upon the pocket.

5. A sealable container comprising, in combination: a container carrying an external ridge extending thereabout adjacent an open end; a cap formed with an internal groove to interlock with said ridge; the margin of the opening of said cap turned inwardly and upwardly to provide a pocket for reception of sealing material.

6. A sealable container comprising in combination: a container carrying an external ridge about its exterior adjacent an open end; the surface of said body flaring outwardly below said ridge portion; a cap formed with an internal groove to be forced into engagement with 15 said ridge when the cap is applied; and an inwardly and upwardly opening pocket carried by the skirt of said cap to carry flowable sealing material to be expelled by contact with said flaring surface by forced application of said 20 cap.

7. A sealable container comprising, in combination: a container carrying an external ridge extending thereabout adjacent an open end; a cap formed with an internal groove to interlock 25 with said ridge; an inwardly and upwardly opening pocket carried by said cap to carry a supply of sealing material to be expelled between the cap and container by pressure upon the pocket, and a body of absorbent material in said pocket 30 to be initially saturated with said sealing material.

8. A sealable container comprising, in combination: a container carrying an external ridge extending thereabout adjacent an open end; a cap formed with an internal ridge to interlock 35 with said first named ridge when the cap is applied; said last named ridge formed with an inwardly and upwardly opening pocket for reception of initially flowable sealing material to 40 be expelled therefrom by pressure to flow between the opposed surfaces of said cap and container.

9. A sealable container and closure therefor comprising, in combination: a container-body member; a closure member; an upwardly opening, collapsible pocket carried by one of said members in position to bring the pocket opening between opposed surfaces of the members when assembled; and a body of sealing wax carried 45 wholly in said pocket; whereby compression of said pocket after at least partial assembly of said members while said wax is in liquid condition will cause the sealing wax to be expelled from the pocket to flow and congeal between 50 said surfaces.

ELIZABETH M. CARHART.
